UNITED STATES PATENT OFFICE.

HARRY O. BRAWNER, OF ROLAND PARK, MARYLAND.

DESIGN FOR A BOTTLE.

41,238.

Specification for Design.

Patented Mar. 14, 1911.

Application filed October 7, 1909. Serial No. 521,624. Term of patent 14 years.

To all whom it may concern:

Be it known that I, HARRY O. BRAWNER, a citizen of the United States, residing in Roland Park, Maryland, have invented a certain new, original, and ornamental Design for Bottles, of which the following is a specification, reference being had to the accompanying drawing, forming part thereof, the figure illustrating the design in perspective.

I claim:—

The ornamental design for a bottle, as shown.

HARRY O. BRAWNER.

Witnesses:

JNO. H. PATTERSON,
SIFFORD PEAM.

Copies of this design may be obtained for five cents each, by addressing the "Commissioner of Patents, Washington, D. C."
